WIRE-DRAWING MACHINE

Charles D. Johnson, Worcester, Mass., assignor to
 Johnson Steel & Wire Company, Inc., Worcester,
 Mass., a corporation of Massachusetts

Application August 1, 1939, Serial No. 287,711

1 Claim. (CL 205—20)

This invention relates to wire-drawing machines and particularly to the wire-drawing block.

One of the objects of the invention is to provide a novel means for water-cooling the block, and in accordance with the invention, the block is a chambered block and provision is made to introduce water to the interior of the block through the shaft on which the block is mounted and by which it is rotated.

10 In order to give an understanding of the invention, I have illustrated in the drawing a selected embodiment thereof which will now be described, after which the novel features will be pointed out in the appended claim.

15 In the drawing:

The single figure is a vertical sectional view through a wire-drawing block embodying my invention.

In the drawing, 1 indicates the wire-drawing block which is formed with the usual wire-receiving surface 2 on which the wire 3 is wound after it has been drawn through the die 4. This block 1 is mounted on and is rotated by a suitable driving shaft 5 which may be operated in any usual way as by means of the intermeshing bevelled gears 6, one of which is mounted on the shaft 5, and the other of which is mounted on the driving shaft 7.

The block 1 is shown as having associated therewith a slow moving rotatable dry lubricant carrying member 8 similar to what is shown in my co-pending application 239,107, filed November 5, 1938. This lubricant carrying member 8 is situated concentrically with the rotary block and is provided with an open-topped lubricant-containing chamber 9 adapted to receive dry lubricant for lubricating the wire and the wire-receiving surface of the drum. 10 indicates a stationary plow element located within the chamber 9 and acting to plow the dry lubricant against the drum as the member 8 is rotating.

The lubricant carrying member 8 is shown as mounted on a sleeve 11 through which the shaft 5 extends, said sleeve being journaled in the frame 12 of the wire-drawing machine.

45 Means are provided for driving the sleeve 11 at a slower rate than that at which the drum 1 is driven, and for this purpose, said sleeve is provided with a gear 13 which meshes with and is driven by a driving gear 14. The construction and operation of the lubricant containing member 8

is similar to that illustrated in my co-pending application, Serial No. 239,107.

The block 1 is provided with an interior chamber 15 and means are provided for cooling the block by introducing water into the chamber through the shaft 5, and delivering the water against the walls 16 of the chamber 15.

For this purpose the shaft 5 is a tubular shaft and there is provided a water supply pipe 17 which extends through the bore 18 of said shaft 5. This supply pipe is stationary and is connected to any suitable source of water supply. Said pipe at its upper end leads into a hollow head member 19 which is provided with one or more laterally extending spray pipes 20 that are constructed to deliver jets of water against the interior wall 16 of the block.

In the operation of the device, the water supply pipe 17 and the nozzle pipes 20 serve to deliver water or other cooling liquid against the wall 16 of the drum as the latter is rotated, thereby keeping the wire-receiving surface of the drum cool. The supply pipe 17 is somewhat smaller than the bore 18 of the tubular shaft 5 and the space between the pipe and the shaft provides a drain outlet through which the water may drain after it has performed its cooling function.

The block 1 is shown as having a removable cap piece 21 which normally closes the upper end of the chamber 15. This cap piece, however, can be readily removed whenever it is necessary to obtain access to the head 19 and spray pipes 20.

I claim:

A wire-drawing machine comprising a chambered wire-drawing block, a vertical tubular shaft on which the block is mounted and by which it is rotated, a water supply pipe extending axially through said shaft and into the chamber of the block, a hollow head secured to said pipe and located within said chamber and into which the pipe delivers water for cooling the drum, and a plurality of spray pipes extending radially from said head member and arranged to deliver said water against the walls of the chamber in the block at a plurality of points circumferentially thereof, the supply pipe being smaller than the interior diameter of the tubular shaft, thereby providing a passage for water to drain out the chamber through said shaft.

CHARLES D. JOHNSON.
